Primary Examiner — Mary Ann Calabrese(74) *Attorney, Agent, or Firm* — K&L Gates LLP**CLAIM**

(57) The ornamental design for a drug administration safety label, as shown and described.

DESCRIPTION

FIG. 1 is a front view of one embodiment of a drug administration safety label of our new design, that portion shown in broken lines is not part of the claimed design and is provided for environmental purposes only.

FIG. 2 is a front view of an alternative embodiment of a drug administration safety label of our new design, that portion shown in broken lines is not part of the claimed design and is provided for environmental purposes only. The drawing is lined for color.

FIG. 3 is a front view of an alternative embodiment of a drug administration safety label of our new design, that portion shown in broken lines is not part of the claimed design and is provided for environmental purposes only; and,

FIG. 4 is a front view of an alternative embodiment of a drug administration safety label of our new design, that portion shown in broken lines is not part of the claimed design and is provided for environmental purposes only. The drawing is lined for color.
